UNITED STATES PATENT OFFICE.

ALBERT E. PAGE, OF BROOKLYN, NEW YORK, ASSIGNOR TO SCOTT AND WILLIAMS, INC., OF NEW YORK, N. Y., A CORPORATION OF MASSACHUSETTS.

CIRCULAR-KNITTING MACHINE.

Application filed April 7, 1925. Serial No. 21,393.

This invention relates to circular knitting machines and more particularly to means for controlling the knitting elements. It includes a continuously rotating element which, 5 while it is peculiarly useful as auxiliary pattern means in producing recurrent sequences of pattern such as tucking or striping, can be employed to control the needles, sinkers or yarn fingers for any purpose. The mechanism has only a few simple parts which are easy to operate and broad in the scope of 10 selections which they can make. At the same time the mechanism is ideal in its cooperation with the knitting elements and all the 15 other selecting devices.

For purposes of illustration the invention will be shown and described as a tucking attachment for the well known Scott and Williams type of seamless hosiery machine, but 20 it is not limited to use as that particular type of attachment or on that particular type of circular knitting machine.

In the drawings, Fig. 1 is a plan view of the head and table of a machine showing 25 the invention embodied as a tucking attachment;

Fig. 2 is an elevation on the line 2—2 of Fig. 1 looking at the auxiliary needle cams and the mechanism operating them from the 30 right side of the machine, the horizontal pattern wheel not being shown;

Fig. 3 is a rear elevation of the tucking attachment and the elements necessary to its 35 operation;

Fig. 4 is a rear elevation of the levers controlling the auxiliary needle cams taken on the line indicated by arrow 4, Fig. 1;

Fig. 5 is a cross section on the line 5—5 of Fig. 1 showing the mounting of the auxiliary 40 needle-cams; while

Fig. 6 is a development of the cylinder cams showing the needle butts and jacks.

The principal element in my invention is a horizontal device 150 revolving continuously 45 at a different angular speed from that of the revolving elements of the knitting head and preferably at a speed in which one revolution equals several revolutions of said knitting elements. I prefer to locate this element—which may be termed a horizontal pattern wheel—above the bed plate of the machine adjacent to the knitting head. It is 50 driven from the usual segment driving pinion 38 on the main drive shaft 32 of the knitting machine by means of a train of gears. This

train of gears includes the usual segment driving gear 60 on the shaft 55 meshing with the pinion 38, and a gear 143 on a short horizontal shaft 144 covered by a guard 142. On the shaft 144 is a bevel pinion 145 meshing with a bevel gear 146 fast on an upright shaft 147 rising above the table C of the machine. This upright shaft 147 is mounted in a sleeve of a bracket 148 bolted to the table C by screws 149. The upper two screws 60 65 149 are set screws to adjust the relation of the gears 143 and 60 and should be set before the lower screw 149 is tightened. The bracket fits around the usual bobbin stand rod E both above and below the usual boss 70 small c in the table C through which the rod passes. This rod can be lifted out of the boss small c and bracket 148 by loosening the usual set screws c₂. The horizontal pattern wheel 150 rotates on the rod E as an axis. 75 The wheel is connected to the upright shaft 147 by a gear 151 which is fastened to the bottom of the wheel by screws (not shown), and setting means on the upper end of the upright shaft 147. These setting means include a loose gear 152 on the shaft 147 meshing with the gear 151 and a collar 153 set tight on the upright shaft 147 above this loose gear by a set screw 154. In the collar 80 85 153 is a setting pin 155 constantly pressed against the loose gear by a spring (not shown). In the upper surface of the loose gear is a hole (not shown), adapted to receive the setting pin when the pin and hole are in register.

It will be apparent from the above description that the horizontal pattern wheel 150 will be driven continuously by the main drive shaft at a speed bearing a constant relation to the speed of the needle cylinder. 90 I prefer to gear it to such a relative speed that the needle cylinder always is in the same angular position at the completion of a revolution of the horizontal pattern wheel 150. In other words, while the needle cylinder is making several completed revolutions the horizontal pattern wheel is making one revolution and any time the horizontal pattern wheel is in any given angular position the needle cylinder will always be found in 105 one certain angular position. In the machine shown in the drawings the wheel is geared to make one revolution while the needle cylinder is making eight revolutions. If the horizontal wheel were geared to turn faster 110

than the needle cylinder; then any given angular position of the needle cylinder would always find the horizontal pattern wheel in one certain angular position, provided the horizontal pattern wheel were making even and not fractional revolutions to one revolution of the needle cylinder.

In addition to maintaining the timing of the horizontal wheel with the needle cylinder, it is necessary that this wheel be kept in time with various selecting devices operated by the pattern chain. In the machine shown in the drawings, the pattern chain is racked every 4 courses and it takes 3 racks of the chain, i. e., 12 courses to pass one link. If at any time the pattern chain is advanced by hand, it may be racked a fractional part of a link and thus in the arrangement shown in the drawings put the selecting devices controlled by the chain four courses ahead of the wheel 150. In the machine shown in the drawings, the wheel 150 is geared to make one revolution while the knitting cylinder is making 8 revolutions as already described, and the upright shaft 147 carrying the setting pin is geared to make 2 revolutions for every revolution of the wheel. Since the upright shaft can be advanced one revolution with relation to the wheel by lifting the setting pin out of the setting gear 152 and allowing it to fall back into the hole in that gear after one revolution of the upright shaft, it will be apparent that by this operation the wheel 150 can be set back half a revolution with relation to the needle cylinder. As long as the number of revolutions of the needle cylinder corresponding to one revolution of the upright shaft 147 equals the number of revolutions of the needle cylinder occurring during one racking of the pattern chain it will always be possible to put the wheel 150 and the pattern chain in time, no matter how far the pattern chain is advanced by hand and no matter how slowly the drum is geared to turn. It will be noted that the needle cylinder and horizontal pattern wheel cannot get out of time and that the pattern chain and horizontal pattern wheel can always be put back in time very easily if the pattern chain is put out of time by being racked by hand.

As already explained, my invention is peculiarly useful in operating needle control elements such as the auxiliary needle cams and in the drawings I have shown my invention operating a raising cam 25 and a lowering cam 4 in such a manner as to produce two courses of tuck stitches alternated with six courses of plain work. The location and interaction of these cams with the needles and jacks is substantially the same as that shown and described in co-pending application for Robert W. Scott, Ser. No. 559,506, filed May 9, 1922, Patent #1,641,554 dated 65 September 6, 1927 this use of my invention

being confined to the means operating the two auxiliary needle cams above mentioned. The function of the lowering cam 4 is to draw the needles down to a level at which they will ride along the surface of right hand side cam 40 and pass under the leading stitch cam 360 unless raised again by some other means. Every other needle has a jack 380 which rides against its cam 366 just after the needle has passed the lowering cam 4. The needles with jacks are lifted back to the normal path above the leading stitch cam 360, while the jackless needles travel below cam 360 and are raised by lower center cam 9 to take yarn without clearing their loops, thus making tuck stitches. The principal function of the raising cam 25 is to raise above the lowering cam 4 the butts of the needles on which tuck stitches are not desired.

The auxiliary lowering cam 4 is mounted on a bracket 430, bolted to the bedplate C of the machine, by means of a slide 431 which passes completely through an upright arm of the bracket and has its outer end bent over as shown in Fig. 5. On this bent-over end is a horizontal set screw 432 adapted to take against the outside of the bracket and determine the distance which the slide can move toward the needle cylinder. The cam 4 is fastened to the inner end of the slide and there is a spring 433 in the upright arm of the bracket tending to keep the cam and slide as far towards the needle cylinder as the set screw 432 will permit. The lever operating the lowering cam 4 is a bell crank lever 434 pivoted on the bracket 430 by a screw 435, one end taking under the bent-over end of the slide 431 as shown in Fig. 5. This bell crank lever is controlled from the main pattern drum 120 by a thrust rod 461, and from the horizontal pattern wheel 150 by a drum cam 156 on the periphery of the wheel. Attached to the upper end of the thrust rod 461 is a cam plate 23 adapted to bear against the free end of the bell crank lever 434, in such a manner that when the thrust rod is raised the bell crank lever pulls the lowering cam 4 away from the butts of the needles. The thrust rod 461 is operated by a two step cam 501 on the main pattern drum 120. The lower step of the cam 501 on the main pattern drum is of such a height that when the thrust rod 461 is on it the lowering needle cam 4 is partially withdrawn until it can take down only the needles having long butts ⁿ1. When the thrust rod is on the higher step of the cam 501 the auxiliary lowering needle cam 4 is entirely withdrawn from contact with the needle butts. The element providing contact between the bell crank lever 434 and the horizontal pattern wheel 150 is an adjustable foot 436 projecting from the free end of the lever toward a drum cam 156 on the horizontal pattern wheel 150. This adjustable foot 436 is held

in a groove on the under side of the bell crank lever, and the extent to which it projects from the lever is adjusted by an eccentric on the foot bearing against the lever. The end of 5 the lever taking under the bent-over end of the slide 431 is pivoted and its angle is adjustable by a similar eccentric. The adjustment of these eccentrics on the lever should be such that when the foot is on the drum 10 cam 156, the lowering cam 4 takes down only the needles having medium butts n^2 or long butts n^1 .

The auxiliary raising needle cam 25 is mounted on one end of a bracket 424 pivoted 15 on pin 425 located under the slide 431 (Fig. 5), and is controlled by a drum cam 157 on the horizontal pattern wheel 150. To the opposite end of the bracket is pivoted a link 427 passing to the drum cam through a slot in a 20 guide plate 428 which is fastened on the lowering cam bracket 430. This link 427 is made in two pieces to provide adjustment. There is a coiled spring 426 tending to hold the raising cam 25 in engagement with the needle 25 butts. The raising cam 25 and its operating elements are so adjusted that when the link 427 is on the drum cam 157, the lowering cam is out of engagement with all the needle butts, and when the link is off the drum cam, the 30 raising cam is in position to raise the needles having medium butts n^2 and long butts n^1 . If desired the cam 25 can be disconnected from the drum cam 157 by means operated by the main pattern drum in the same way in 35 which it is withdrawn from the needle butts in R. W. Scott's Patent #1,641,554 above mentioned.

Assuming that the machine is to make ribbed instep stockings with tuck stitches, 40 knitting from toe to top, the tucking could be accomplished in the manner now to be described. When the ribbed instep is to be commenced the thrust rod 461 is on the lower step of the cam 501, putting the auxiliary 45 lowering cam 4 in a middle position where it can take down the needles having long butts n^1 . The long butt needles divide immediately after passing under the lowering cam 4, every other needle being raised over the leading stitch cam 360 and under the top center cam 357 by its jack 380 riding up the jack cam 366. The jackless needles pass under the leading stitch cam and over the lower center cam 9 making tuck stitches. The instep needles are the ones with long butts and therefore it is the instep which is tucked. The 55 medium and short butt needles are not drawn down by the auxiliary lowering cam 4 and therefore do not tuck at this point. When 60 the machine is ready to put in tuck stitches all the way round the stocking, the thrust rod 461 drops off the cam 501 onto the main pattern drum 120 and the lowering cam 4 goes all the way in and draws down all the 65 needles.

The alternation of two tucked courses with six plain courses is obtained by use of the horizontal pattern wheel. During the second course of tuck stitches and while the long butt needles are being taken down by the 70 lowering cam 4, the drum cam 157 on the wheel 150, which has been holding the raising cam 25 out of action, lets drop the link 427. The raising cam 25 then goes into action lifting the long and medium butt needles over 75 lowering cam 4. The positions of the needle butts and cams at this moment are shown in Fig. 6, the long and medium butts being shown solid and the short butts dotted. While the medium and long butt needles are 80 passing over the raising cam 25, the drum cam 156 comes around to the foot 436 of the bell crank lever and withdraws the lowering cam 4 till it just misses the low butts. When changing from plain to tuck courses, drum 85 cam 157 removes the rising cam 25 from action while the short butt needles are opposite it, and when the long butt needles are next on the lowering cam 4 the foot of the bell crank lever drops off the drum 156, the lowering cam goes all the way in and when the short butt needles come around again they 90 will be drawn down.

It should be noted that if at any time it is desired to change the relative speeds of the 95 needle cylinder and horizontal pattern wheel this can be accomplished by simply substituting another pair of gears for gears 151 and 152. Many other changes will occur to those skilled in the art, which do not depart from 100 the scope of my invention.

What I claim is:—

1. In a circular knitting machine a circumferentially free horizontal pattern means mounted on a vertical axis above the bedplate 105 of the machine, in combination with means below the bedplate revolving said pattern means continuously in timed relation to the knitting head at angular and circumferential speeds differing from those of the knitting 110 head.

2. In a circular knitting machine, a circumferentially free horizontal pattern means mounted on a vertical axis above the bedplate of the machine, and means below the bedplate 115 revolving said pattern means continuously in timed relation to the knitting head at an angular speed less than that of the knitting head, in combination with lever means separate from said horizontal pattern means, but adapted to be actuated from said horizontal pattern means, to control the knitting elements.

3. A circular hosiery knitting machine having a main drive shaft, a horizontal pattern wheel revolving continuously at an angular speed less than that of the knitting head and located above the bedplate of the machine, and cams on said wheel, in combination with lever means adapted to transmit the se- 125 130

lections of the cams to the knitting head, and other pattern means adapted to cause disconnection of said lever means from said cams.

4. A circular knitting machine having a horizontal pattern wheel adjacent to but not touching the knitting head and adapted to revolve continuously at an angular speed of one revolution to a plurality of complete revolutions of the knitting head.

19 5. A circular knitting machine having a continuously revolving horizontal pattern wheel on a vertical axis, cams on the periphery thereof, and lever means adapted to transmit the selections of said cams to the knitting elements, in combination with an intermittently moving pattern means adapted to cause disconnection of said lever means from said cams.

6. A circular knitting machine having a knitting head, and a pattern chain adapted to be racked after a certain number of revolutions of the knitting head, in combination

with a horizontal auxiliary pattern wheel on a vertical axis adapted to be revolved continuously at an angular speed of one revolution 25 to one or more rackings of the pattern chain.

7. A circular knitting machine having a main drive shaft, a knitting head driven therefrom, a pattern chain adapted to be racked after a certain number of revolutions 30 of the knitting head, a train of gears, and a horizontal auxiliary pattern wheel on a vertical axis adapted to be revolved continuously from the main drive shaft by said train of gears at an angular speed of one revolution 35 to one or more rackings of the pattern chain, in combination with means in said train of gears adapted to permit setting of said horizontal auxiliary pattern wheel forward or back an amount equal to one racking of the 40 pattern chain.

In testimony whereof I have signed my name to this specification.

ALBERT E. PAGE.
